CLAIM

The ornamental design of a jacket, as shown and described.

DESCRIPTION

FIG. 1 is a front view of the jacket in accordance with the design;

FIG. 2 is a rear view thereof;

FIG. 3 is a side view thereof;

FIG. 4 is a side view thereof with the arm of the jacket raised;

FIG. 5 is a perspective view thereof;

FIG. 6 is an inside view thereof with the jacket opened; and, FIG. 7 is a top view thereof.

The longer broken lines shown in the drawings illustrate stitching that forms part of the claimed design. The shorter broken lines shown in FIG. 6 illustrate portions of the jacket that form no part of the claimed design.

1 Claim, 7 Drawing Sheets
